ATTORNEY

UNITED STATES PATENT OFFICE.

JOHN G. KOENEN, OF MOUNT VERNON, NEW YORK.

DESIGN FOR AN EYEGLASS-CASE.

SPECIFICATION forming part of Design No. 24,735, dated October 8, 1895.

Application filed August 17, 1895. Serial No. 559,678. Term of patent 14 years.

To all whom it may concern:

Be it known that I, JOHN G. KOENEN, a citizen of the United States, and a resident of Mount Vernon, in the county of Westchester 5 and State of New York, have invented and produced a certain new and useful Design for Eyeglass-Cases, of which the following is a specification.

Reference is to be had to the accompanying 10 drawings, forming a part of this specification, in which drawings—

Figure 1 is a plan view of an eyeglass-case, showing my design. Fig. 2 is a front view of the same, and Fig. 3 is a sectional view on 15 the line 3 3 of Fig. 2.

The leading feature of my design consists in the eyeglass-case provided with a raised surface at or about the center of one of the

members of the eyeglass-case sloping to a point adjacent to the edges of the case. 20

A is the bottom member of the case, and B the lid. The edges C of the said members A B are straight and parallel, while the edges D are curved, as shown. At the center of the lid B appears a raised surface a. This raised 25 surface joins the main outer surface of the lid B by salient bevels or slopes c c, as shown clearly in Fig. 1.

What I claim is—

The design for eye-glass cases substantially 30 as shown and described.

JOHN G. KOENEN.
